CLUTCH MECHANISM FOR ELECTROMAGNETIC SOUND RECORDING AND REPRODUCING DEVICES

Semi Begun, Berlin, Germany, assignor to C. Lorenz Aktiengesellschaft, Berlin-Tempelhof, Germany, a company

Application June 6, 1935, Serial No. 25,352
In Germany June 9, 1934

1 Claim. (Cl. 192—43)

The invention relates to electromagnetic sound recording and reproducing devices of the kind having a steel tape or wire as a sound record carrier such as is customary especially with the so-called Poulsen method. This tape or wire is in a well-known manner arranged on two spools or drums in order alternately to be wound onto one spool and then from this onto the other spool. In each case one of these spools is pulling at the 10 tape or wire. As soon as the movement of the tape or wire is to be reversed for well-known reasons, the spool that has been pulling at the tape or wire is disconnected from the drive, and the other spool in its turn attached thereto in order now to pull at the tape or wire.

The invention has for its object to provide coupling means by which the parts moved in this way by means of either one or the other of the spools shall be completely and automatically disconnected from the motor shaft. In addition, 20 the connecting and disconnecting shall be effected within the shortest possible time and with the least expenditure in means. In order to perform this a clutch is employed whose action solely depends upon the direction in which one of the 25 two clutch members is rotated.

One embodiment of the invention is described hereinafter by way of example, reference being had to the accompanying drawing in which

Fig. 1 is a partially sectioned elevation of one of the spools, its clutch and part of the drive, and Fig. 2 shows a section on the line 2—2 of Fig. 1.

The clutch is comprised of two members 1, 2. Member 1 is constructed as a belt pulley, adapted to be driven by a belt 3 by which it is in connection with a motor not shown. Member 2 carries a spool 4 which is one of the two spools that in a well-known manner are provided with a steel wire 5 adapted to be wound from one spool onto the other alternately. Instead of the wire 5 a tape or the like may be disposed to serve as a sound record carrier. Two studs 7, secured to member 1, are each fitted with a jaw 6 rotatably mounted on these studs. The jaws 6 are thus disposed eccentrically with respect to parts 1, 2. As will be seen from Fig. 2, the jaws 6 each have a curved edge facing the inner cylindrical surface of the member 2. Each jaw has a slot 13. Rotatably mounted on a trunnion 10 of the member 1 is a disc 8 provided with two pins 9. These each project into one of the slots 13. The disc 8 has two arcuate slots 11 through which the studs

7 extend. The slots 11 are concentric with respect to trunnion 10. A brake block 12 contacts with the circumference of the disc 8.

The mode of action is as follows.

When clutch member 1 is rotated in the direction of the arrow shown in full lines in Fig. 2, the studs 7 slide within the slots 11 as indicated by a full-line arrow. The jaws 6 are thus moved on the pins 9 in a direction likewise denoted by a full-line arrow, so that their curved edges are withdrawn from the clutch member 2. Disc 8 is by the brake block 12 prevented from rotating on trunnion 10 until the studs 7 come against the respective ends of the slots 11, when the friction between the parts 8 and 12 is overcome so that the parts 1, 7, 6, 9, 8 will now rotate conjointly, the part 2, 4 however not sharing in this movement since the jaws 6 have been so moved on the pins 9 that they do not contact with clutch member 2.

It will thus be seen that by reversing the movement of the belt 3 the movements of the parts 1, 7, 6, 9, 8 will be those indicated by the dotted-line arrows, so that the curved edges of the jaws 6 are brought to contact with the clutch member 2 and thus cause the part 2, 4 to be driven by means of member 1.

The jaws 6 preferably consist of hard paper provided with an insertion of cloth, in order that they shall be efficient and noiseless in their action.

It will be evident that the usual second spool allotted to spool 4 in order to carry the wire 5 is likewise fitted with a clutch constructed as herein described.

What is claimed is:

In a clutch mechanism for a magnetic sound recording and reproducing machine, a first clutch member coupled to a spool for carrying tape or wire, an intermediate disc continuously maintained under influence of a braking means, a second clutch member connected to a driving shaft, a plurality of jaws fulcrumed on said second clutch member and arranged to cooperate with said first clutch member, means on said disc for controlling the cooperation of said jaw members with said first clutch member, said disc being provided with slots cooperating with means on said second clutch member for limiting the relative movement between said disc and second member.

SEMI BEGUN.
